GIOVANNI EMANUELE ELIA, OF PARIS, FRANCE, ASSIGNOR TO VICKERS LIMITED, OF WESTMINSTER, ENGLAND.

SAFETY-ANCHOR FOR SUBMARINE MINES.

1,153,774.

Specification of Letters Patent. Patented Sept. 14, 1915.

Application filed September 15, 1914. Serial No. 861,833.

To all whom it may concern:

Be it known that I, GIOVANNI EMANUELE ELIA, a subject of the King of Italy, and residing at Hotel de Crillon, Place de la Concorde, Paris, France, gentleman, have invented certain new and useful Improvements in and Relating to Safety-Anchors for Submarine Mines, of which the following is a complete specification.

10 This invention relates to safety anchors for submarine mines the object of the invention being to permit of the mine being manipulated without danger prior to its being submerged but insuring a rapid operative positioning when struck by a moving ship.

A construction embodying the invention is shown, by way of example, in the accompanying drawing, in which:

20 Figure 1 is a view of the mine with its anchor in the relative position which these elements occupy before launching; Fig. 2 is a partial section showing the details of the mine connections; Fig. 3 is a section 25 taken on the line 3—3 of Fig. 2; Figs. 4 and 5 show details; Fig. 6 shows the mine in the anchored position.

The buoy rope (not shown) coming from the mine anchor *a* is connected in any suitable manner to the socket *b* adapted to slide on a cylindrical hub *c* rigidly connected to the mine, comprising the operating members for the percussion device. The sliding movement of the socket is limited by the 35 pins *d* of which there are three for instance (Figs. 1 and 3) screwed on the hub *c* and traversing the socket *b* through elongated openings *e* (Fig. 1).

The hub *c* supports, for instance, three 40 stirrup members *f* to which a cap *g* is articulated (Figs. 2 and 4) supporting the securing point *h* of a cable the other end of which is integral with a frame *j*, preferably circular, provided at the upper part of the 45 mine where it bears on the brackets *k* each of which is formed with an opening *m* for the passage of the cable *i*. This frame *j* has a diameter greater than that of the body *n* of the mine so as to provide a projection on 50 the said mine which will be struck first by a moving ship whatever the angle at which the ship strikes the mine.

Each of the caps *g* is located in a notch 55 formed in the socket *b* and is provided with a projection *o* covered by this socket when

in the inoperative position. The socket is held upon each cap in the safety position illustrated in Figs. 1 and 2, by a screw *p* the resistance of which is calculated in such a manner as to resist the tractive efforts 60 which may be produced during the manipulation of the mine before and during its launching and so as to resist the buoyancy of the mine when the latter is moored.

The operation is as follows:—Before 65 launching the mine the elements occupy the relative positions shown in Figs. 1 and 2, the firing mechanism being maintained without possibility of movement of the percussion pin, by the socket *b*. When the mine is launched it separates from its bearing (Fig. 6) but the locking members preserve the relative position shown in the drawing, the traction due to the buoyancy of the mine being supported entirely by the 70 three screws *p*. When a moving ship comes into contact with the mine, a shock is produced which is absorbed entirely by the circular frame *j* projecting on the body of the mine so that under the effect of this shock 75 the three screws *p* are cut through. Owing to the buoyancy of the mine the latter rises as much as is permitted by the pins *d*. In this position the frame *j* remains in position 80 on the mine but the caps having no connection with the socket *b* of the mooring cable can effect a rotary movement with respect to this socket under the effect of the friction of the hull of the ship. The movement of rotation of the mine with respect to the anchoring cable causes, in the well known manner, the unscrewing of one of the two screw-threaded parts which join the mine body to the socket or hub *b*. The mine body is then 85 free to move upwardly, thus cocking and releasing the striker which causes the explosion of the mine. This arrangement possesses the advantages of being completely insensitive to currents and also to the explosions of neighboring mines, the currents and the 90 waves produced by such explosions acting on all faces of the frame *j* so that there is no action on the caps *g*.

The frame *j* may be of any shape and may be rendered integral with the mine in any 105 suitable manner, provided that it should be integral with the latter in the direction of rotation. Similarly the connection between this frame and the rupturing members may be effected in any other manner than that 110

illustrated although the disposition described is the preferred construction owing to the facility of mounting provided by the disposition of the caps. 9.

5 The invention is applicable to submarine mines of any type in order to increase the safety thereof.

What I claim is:—

1. A submarine mine provided with an anchor resting on the ground of the sea, an anchor cable connected to the mine body through screw-threaded parts of opposite pitch, a shock member projecting upon the mine over all angles of approach a vessel 10 may assume, and safety devices with which the shock member is connected, the safety devices locking the screw-threaded parts and preventing any movement of rotation of the mine, relative to its anchor cable.
2. A submarine mine provided with an anchor resting on the ground of the sea, an anchor cable connected to the mine body through screw-threaded parts of opposite pitch, a frame mounted on the mine body 15 and projecting thereupon over all angles of 20
- 25

approach a vessel may assume, a safety socket forming part of the anchorage cable, articulated caps connected to said safety socket, and ropes or cables connecting said frame to said articulated caps.

3. A submarine mine provided with an anchor resting on the ground of the sea, an anchor cable connected to the mine body through screw-threaded parts of opposite pitch, a frame mounted on the mine body 30 and projecting thereupon over all angles of approach a vessel may assume, articulated caps, ropes connecting said frame to said caps, a socket forming part of the anchorage cable and guided through pins on a hub 35 forming part of the striker, and rupturing screws connecting said articulated caps with said socket.

In testimony whereof I have hereunto set my hand at Rome, this second day of September, 1914.

GIOVANNI EMANUELE ELIA.
